ATTORNEY.

UNITED STATES PATENT OFFICE.

FRANCES C. ZIMMERMAN, OF CINCINNATI, OHIO.

GLUE DISSOLVER AND CONVERTER.

Application filed May 19, 1927. Serial No. 192,666.

This invention relates to glue converters or dissolvers, and particularly to certain improvements in the apparatus patented by Charles M. Zimmerman, #989,101, granted

5 April 11, 1911.

The construction illustrated in this patent shows a glue jelly containing vessel which discharges into a catch basin, which in turn discharges into a glue reservoir or container.

10 The vessel and the catch basin are illustrated as being disposed within an outer tank and steam is illustrated as being discharged into the interior of this tank and circulating around the glue dissolving vessel and around 15 the catch basin. In this construction, however, the catch basin is separated from the glue dissolving vessel so that steam circulates not only around the dissolving vessel and catch basin but enters into the dissolving vessel and comes in contact with the glue. Inasmuch as it is essential that the glue shall be mixed in certain quite accurate proportions with the water so as to give a certain definite consistency to the glue, the 20 circulation of the steam in contact with the glue tends to cause the glue to take up an additional amount of moisture and thus change the consistency from what has been predetermined.

25 The general object of the present invention is to provide a construction of this character wherein the glue dissolving vessel has steam-tight contact with the catch basin so that though the dissolving vessel may be 30 removed from its engagement with the catch basin to permit the thorough cleansing of the catch basin, yet the steam will not come in direct contact with the glue.

35 A further object is to provide a screen disposed within the catch basin for the purpose of preventing the passage of any undissolved glue into the glue reservoir.

40 Other objects will appear in the course of the following description.

45 My invention is illustrated in the accompanying drawing, wherein:—

The figure is a vertical sectional view through a glue converter constructed in accordance with my invention.

50 Referring to the drawing, 10 designates an outer vessel or tank, which is supported in spaced relation by means not shown to a dissolved glue tank 12, beneath which is a tank 13 for the water of condensation. Disposed 55 within the container or tank 10 is a circular

catch basin 14, the lower end of which is contracted, as at 15, and is provided with a downwardly extending tube 16 which passes through the bottom of the tank 10 and into the melted glue chamber 12 so as to discharge melted glue thereinto. This catch basin 14 is held in position within the tank 10 in any suitable manner as, for instance, by the outwardly projecting centering arms 17. The upper end of this catch basin is 60 formed with an overturned bead 18, and disposed within the catch basin and resting upon the lower end thereof is the screen 19, this screen acting to retain any lumps of undissolved glue and prevent these lumps of 65 undissolved glue from passing downward into the glue pot or glue chamber 12.

70 Adapted to rest upon and be supported by the catch basin 14 is the glue dissolving and melting vessel 20. The bottom of this vessel is formed to provide a bead 21 which fits over the bead 18 and has practically steam-tight contact therewith so that the steam cannot pass up between the top of the catch basin and the bottom of the vessel 20. Within the 75 circle defined by the bead 18, the bottom of the vessel 20 is perforated, as at 22, so as to permit the dissolved glue to pass into the catch basin. The upper end of the vessel 20 is provided with handles 23 whereby it may 80 be lifted out of the converter.

85 The upper end of the converter has attached thereto the inwardly extending flange 24 constituting a drip trough, and adapted to close the upper end of the converter is 90 the cover 25 provided with handles and having a central opening 26. The cover is formed with a flange 27 which is adapted to fit tightly against the outer wall of the tank or steam chamber 10. Leading from the 95 trough formed by the wall 24 is a duct 28 which leads downward and discharges into the lower portion of the tank 10. Thus any water which is condensed upon the conical cover or lid 25 will be discharged downward 100 into this trough 24 and from thence will pass down into the lower portion of the tank. The tank is provided with a pipe 29 for admitting steam to the interior of the tank, this pipe at its inner end having a distributor 30 105 so as to cause the steam to be evenly distributed within the interior of the tank 10. Suitable means is provided for controlling the amount of steam which will enter or controlling the pressure of this steam. 110

The lower end of the tank 10 is also connected by a pipe 31 to the water chamber 13 so that water condensed from the steam can pass downward into this water chamber. 8 This water chamber is provided with the usual tap from which hot water may be drawn whenever desired, and preferably the water chamber is connected to a source of water supply and provided with a ball cock 10 or some like arrangement for the purpose of causing water to enter the chamber in case the water therein is exhausted. Under ordinary circumstances, however, the 15 condensed steam will supply sufficient water to keep the chamber full. The water in the chamber 13 will keep the dissolved glue hot.

In the use of this mechanism, the vessel 20 is to be filled with particles of glue and a sufficiency of water applied thereto. This 20 vessel is then set into a pan until the glue reaches a jellified state, and then the vessel is removed from this pan and disposed within the converter. The cover is then closed and steam admitted to the interior of the tank 10. The glue within the vessel 20 will be melted or dissolved very quickly by the circulation of steam around the exterior of the vessel and around the catch basin and the dissolved glue will flow downward into 30 the catch basin and so into the glue container 12.

The advantage of the construction which I have devised over that shown in the patent to Zimmerman is that the steam does not 35 come in contact with the glue at all, and further in that the steam causes a more rapid dissolving of the glue by contacting with the bottom of the vessel as well as the side thereof exteriorly of the catch basin and steam surrounds the catch basin so as to 40 keep hot the glue therein and also surrounds the pipe 16. Thus the glue is not only heated within the vessel 20 but the glue falling into the catch basin and somewhat held back by the screen 19 is kept thoroughly heated without, however, coming in direct 45 contact with the steam.

The construction is such that the interior 50 of this catch basin may be very readily cleaned by simply removing the vessel 20, and it is obvious that the catch basin itself may be so formed as to be readily removable by having the neck 16 extend down through an opening in the bottom of the tank 10. 55 This permits the tank 10, catch basin, and the vessel 20 to be thoroughly cleansed of glue. By separating the vessel 10 from the top of the glue container 12, it is possible to provide a lid 11 on the glue container 60 which will permit ready access thereto for the purpose of noting the consistency of the glue and its character at any time. The glue chamber is, of course, provided with a draw-off cock such, for instance, as that 65 shown in the patent to Zimmerman, #971,

337, granted on September 27, 1910. The various parts are preferably made of copper and supported upon legs.

It has been found in actual practice that a glue converter constructed in accordance 70 with my invention melts the glue very quickly and almost instantaneously, and in particular prevents the glue from being contaminated by foreign matter, such as compounds used in cleaning boilers or steam generators which would otherwise come into contact with the glue and become dissolved 75 therein in the process of melting or dissolving the glue if the steam came in direct contact with the glue.

The central opening of the cover provides means whereby any steam which escapes between the top of the glue dissolving vessel and the outer jacket or tank may pass off and the water of condensation from such 85 steam is caught by the trough formed by the wall 24 and carried into the lower portion of the tank. The opening 27 also provides for the workman pouring cold glue 90 back into the converter. By spacing the dissolved glue containing tank 12 from the lower end of the tank 10, I provide for opening the door 11 and thus permit easy 95 access to be had to the interior of the tank 12.

I claim:

1. A glue converter and dissolver of the character described comprising an outer tank having a removable cover and means for admitting steam thereto, a vertically extended catch basin open at its upper end, having a 100 diameter less than the diameter of the outer tank and having its bottom spaced from the bottom of the outer tank and having a discharge pipe extending through the bottom of the tank, and a vessel for containing dissolving glue having a diameter less than the diameter of the tank and adapted to be inserted therein and having substantially steam-tight engagement with the top of the catch basin but removable therefrom, the 105 central portion of the vessel circumscribed by the wall of the catch basin having perforations.

2. A glue converter and dissolver of the character described comprising an outer tank 110 having a removable cover and means for admitting steam thereto, an axially elongated catch basin less in diameter than the tank, open at its upper end and having a discharge pipe extending through the bottom of the tank, the bottom of the catch basin being spaced from the bottom of the tank whereby to permit the circulation of steam all around the catch basin and beneath the same and a vessel for containing 115 dissolving glue having a diameter less than the diameter of the tank and adapted to be inserted therein and having substantially steam-tight engagement with the top of the catch basin but removable therefrom, the 120 125 130

central portion of the vessel circumscribed by the wall of the catch basin having perforations, the catch basin having a removable screen therein.

- 5 3. A glue converter and dissolver of the character described including a tank constituting a steam jacket and having a removable cover having steam-tight engagement with the tank, means for carrying
- 10 water of condensation from the cover to the bottom of the tank, an axially elongated catch basin detachably mounted within the tank having an outer diameter smaller than that of the tank and the bottom of the catch
- 15 basin being spaced from the bottom of the tank and having a tubular portion extending through the bottom of the tank, a glue dissolving vessel removably disposed within the upper portion of the tank and resting
- 20 upon the catch basin, the catch basin having a diameter smaller than that of the vessel and the bottom of the vessel having perforations communicating with the interior of the catch basin, and means for admitting
- 25 steam to the interior of the tank.

4. A glue converter and dissolver of the character described including a tank constituting a steam jacket, the upper end of the tank having an inwardly extending wall forming a trough for the water of condensation, means for conducting water gathering in said trough into the lower end of the tank, an axially elongated catch basin of smaller diameter than the tank and mounted within the tank and spaced at all points from the 30 wall and bottom of the tank and having a tubular portion extending through the bottom thereof, a glue vessel removably disposed within the upper portion of the tank and resting upon the catch basin and having 35 steam-tight engagement therewith, said dissolving vessel having an aperture discharging into the catch basin, the upper end of glue vessel having tight engagement with the inwardly projecting wall, and a cover 40 removably engaging the top of the tank.

In testimony whereof I hereunto affix my signature.

FRANCES C. ZIMMERMAN.
